Application April 15, 1947, Serial No. 741,644

7 Claims. (Cl. 250—41.5)

1

This invention relates to record controlled machines and particularly to sensing and comparing means for data designated on the records.

Comparison of data on records serves various functions in record controlled machines. For instance, in tabulators the comparison of group designating data on records controls interruption of record feed and initiation of total-taking. In collators, comparison of data controls sorting of the records. Heretofore, a separate sensing assembly was used for each record to enter into the comparison. Comparison of data on a plurality of records was accomplished by coordinating connections between the separate sensing assemblies. In electrically operated record-controlled machines, such coordinating connections took the form of circuits with relays controlled by the separate sensing assemblies.

The present invention is directed to and has for its general object the simplification of the sensing and comparing means through the provision of a single sensing assembly or unit for the plurality of records to be compared, with such single sensing unit also serving in itself as comparing means.

More specifically, the invention is directed to and has as an object the provision of a single sensing unit of the optical type to sense and compare data on a plurality of record cards.

According to the invention, the single sensing unit for a plurality of record cards provides a single ray of light which directly and by reflection scans the plurality of record cards concurrently for data. For corresponding columns of the plurality of records, a single photocell surfaces to respond to the light scanning such columns concurrently. Agreement or disagreement of data in the corresponding columns is manifested by the selective energization of the photocell. Hence, the single sensing unit not only incorporates provisions for scanning corresponding columns of a plurality of record cards concurrently for data but also incorporates comparison means for such data.

Another object of the invention is to provide a single sensing and comparing unit for a plurality of records to function for sensing and comparing data represented on the records according to a single-point or combinational-point code.

Data are represented in columns of a record by selectively perforating index positions thereof according to a chosen code. Numerals are usually represented in the single-point code, by selectively perforating so-called 0, 1, 2, . . . 9 index positions of a column. Alphabetic data are usu-

2

ally represented in the combinational-point code, by selective combinations of perforations in index positions 1, 2, . . . 9 and index positions 0, 11, and 12.

5 In the simplest form of the invention, the circuits are arranged for the sensing and comparing of single-point codally represented data on the records. In each machine cycle, records to be sensed and compared will be fed to spaced sensing stations. A single sensing and comparing unit including a photo-sensitive element and an optical system will sense and compare the data on the records at the spaced stations. The optical system which includes projecting and reflecting elements will direct a single ray of light successively upon corresponding index positions of the records at the spaced stations. The ray of light will be directed through perforations in the corresponding index positions upon the photo-sensitive element, activating it as a manifestation of data agreement. If any of the corresponding index positions is blank, it will divert the light ray from the photo-sensitive element, so it will remain unactivated upon a disagreement of data. In this application, the records of the same run all will bear single-point or numerical data to be sensed and compared.

Elements are provided which may be placed in the circuit for controlling the machine according to sensing and comparing of combinational codal data. Repeat activations of the photo-sensitive element will be effected in a cycle as a manifestation of data agreement. In this application, the records of the same run all bear combinational codal or alphabetic data to be sensed and compared.

The invention also provides an alternately effective optical system for activating a photo-sensitive element only upon the sensing of a disagreement of data. This form of the invention is applicable to the sensing and comparison of both single and combinational-point codal data and records bearing either type of data may be included in the same run. When this form of the invention is used, the index points of the record columns to be sensed and compared should preferably not be printed on or otherwise obscured. Further, the surfaces of the records should be white and glossy since these surfaces themselves will serve as light reflecting means.

The records may take the form of individual cards or of sections of a tape or film. Since a perforation in a record is a light-pervious point, it may be referred to as such in the specification and claims. Obviously, in place of perforations,

equivalent light-pervious points may be applied to index positions to designate data.

Other objects of the invention will be pointed out in the following description and claims and illustrated in the accompanying drawings, which disclose, by way of examples, the principle of the invention and the best mode, which has been contemplated, of applying that principle.

The invention will be disclosed as applied, for example, to the card-controlled machine which is the subject matter of Patent No. 2,364,188. Only as much of this machine as is necessary to understand the invention will be referred to herein.

In the drawings:

Fig. 1 is a partly diagrammatic section through the card handling portion of the machine, showing the sensing and the comparing means which is the subject matter of the present invention.

Fig. 2 shows a fragment of a record card.

Fig. 3 is a timing chart of pertinent contacts.

Fig. 4 is a circuit diagram.

Figs. 5 to 8 are diagrammatic views pertaining to different conditions of agreement and disagreement of data on a pair of record cards.

Referring to Fig. 1, the cards to be operated on are stacked in hopper 31. A conventional picker 35 feeds one card each card cycle out of the hopper. Successive pairs of feed rolls 33 and 34 then advance the card during successive card cycles to the delivery hopper 32. The picker and feed rolls are driven only during card cycles through a one-revolution clutch (not shown) which is engaged by energization of a clutch magnet 28 (Fig. 4) and disengaged by deenergization of the magnet. During a card cycle, the picker 35 feeds the bottom card out of hopper 31 to the first set of feed rolls 33 and 34. By the end of the cycle, the card is advanced to a position in which its leading edge just reaches a first sensing station, defined hereby the neck or constricted portion of an aperture A. In the next cycle, the card is fed across the aperture A to a position in which its leading edge just reaches a second sensing station, defined hereby the neck of an aperture B. Meanwhile the following card is advanced to aperture A. In the succeeding cycle, the leading card is fed across aperture B and delivered to hopper 32 while the following card is fed across the aperture A. The cards are fed in synchronism so that as the index positions 9 to 0, 11 and 12 of the leading card successively traverse the aperture B, the same index positions of the trailing card traverse the aperture A, with corresponding positions concurrently crossing the respective apertures. It may be mentioned that the first card fed out of hopper 31 to the aperture A closes card lever contacts 41 (Fig. 4) near the end of the first card cycle, and at a similar time in the next card cycle, the card closes card lever contacts 42 (Fig. 4) as it is fed to aperture B.

In machines of this type, card feed and initiation of total taking are controlled by comparison of group data on the record cards. When the card traversing aperture A has group data different than the group data on the card traversing aperture B, the sensing and comparing means detects the disagreement of group data and brings auto-control means into operation for interrupting card feed and initiating total-taking. One or more card columns may be assigned to the group designating function.

The sensing and comparing means includes a single light ray projector L which throws a concentrated band of parallel rays of light upon the constricted center of aperture B. Assuming

no cards are present at apertures A and B, then, as indicated in Fig. 1, the light band passes to a mirror M which reflects the light to a mirror M₁. Mirror M₁ re-directs the light through aperture A.

The thin rectangle of light projected upon the neck of aperture B has a width; i. e., dimension across the machine, sufficient to scan all the card columns and a length; i. e., dimension in the direction of card feed, equal to or slightly less than the length of a perforation in an index position of the card. The apertures A and B each have a width substantially equal to that of the light beam and a length slightly less than that of an index position of the card. The width of the reflecting surfaces of mirrors M and M₁ is at least equal to that of the aperture. Two other sets of mirrors, MN and MK are provided. Each of mirrors MN and MK has a reflecting surface equal to or slightly less in width than the transverse dimension of a data designating perforation. There is one mirror MN and one mirror MK for each pair of corresponding card columns of the pair of records to be sensed and compared for group data. A suitable arrangement of mirrors MN and MK is indicated in Fig. 1. The mirrors MK_a and MN_a are positioned respectively to receive a light ray reflected from a column of the card at station A or passing through a perforation in this card column and to re-direct the light to photocell K_a or N_a, respectively. A light ray passing through a perforation in the adjacent card column or reflected from a blank index position of this column will go directly to photocell N_b or K_b, respectively. A light ray reflected from or passing through an index position of the next column will strike and be reflected by mirrors MK_c and MN_c to photocells K_c and N_c, respectively. This arrangement may be repeated for every three card columns. The optical system further includes a pair of mirrors M₂ and M₃, each of the same effective width as mirror M or M₁. For a reason explained later, mirror M₂ is hinged so that it may be swung into operative position against a stop 10 or into inactive position against a stop 11.

An analysis will be given below of the working of the optical system with respect to four possible conditions and, for the sake of discussion, it will be assumed mirror M₂ is in operative position and that the card columns under consideration are those to which the mirrors MN_a and MK_a are related.

Case 1—A perforation in the card traversing the second sensing station is crossing aperture B while a like data perforation is traversing aperture A, a condition denoted in Fig. 5. The perforation at aperture B passes a ray of light from projector L to mirror M which reflects it to mirror M₁, in turn directing the light ray through the perforation at aperture A to the mirror MN_a. The mirror MN_a directs the light ray to photocell N_a. Thus, energization of a photocell N is a manifestation of agreement of data designating points in corresponding columns of the leading and trailing cards.

Case 2—A perforation in the leading card is crossing aperture B while the trailing card does not have a corresponding perforation at aperture A, a condition denoted in Fig. 6. The ray of light passed by the perforation at aperture B to mirror M is reflected to mirror M₁ from which it is reflected to the aperture A. The unperforated index position at the aperture A reflects the light, in

the manner of a mirror, to the mirror M_{Ka} which directs the light to photocell Ka .

Case 3—A perforation in the trailing card is crossing aperture A but there is no corresponding perforation in the leading card, a case denoted in Fig. 7. A light ray from projector L is reflected, as from a mirror, by the unperforated index position at aperture B, to mirror M_2 . Mirror M_2 reflects the light ray to mirror M_3 which directs the light through the card perforation at aperture A to the mirror M_{Ka} which, in turn, reflects the light to photocell Ka .

Thus, in cases 2 and 3, a photocell K is energized as a manifestation of disagreement of group data in corresponding columns of cards traversing the first and second sensing stations.

Case 4—There are no perforations, in the leading and trailing cards, at apertures A and B, a condition denoted by Fig. 8. A light ray from projector L is reflected by the unperforated index position at aperture B to the mirror M_2 and thence to mirror M_3 . Mirror M_3 reflects the light ray towards aperture A. The unperforated index position at aperture A reflects the light ray to mirror M_{Na} which directs the light upon photocell Na .

Thus, in cases 1 and 4, a photocell N is energized and the corresponding photocell K is not energized, as a result of agreement of perforations or of blank index positions in the leading and trailing cards. In cases 2 and 3, photocell K is energized while photocell N is not energized, as a result of disagreement of designations in the leading and trailing cards.

Further explanation of the sensing and comparing means will be given in the description of the circuits shown in Fig. 4. These circuits have elements common to circuits shown in the aforementioned patent but the circuits here are revised to fit the requirements of the present sensing and comparing means and to omit elements unnecessary to an understanding of the present invention.

Switch 180 is closed to place power, from a D. C. source, upon opposite circuit lines 191 and 192. To start operations, the operator depresses a start key to close start key contacts 240, establishing a circuit from line 191 through auto-control relay contacts P1, the start key contacts 240 and total cycle cam contacts T8, through card feed clutch magnet 28 and a relay Q, in parallel with magnet 28, and thence to line 192. The first card feed cycle follows. During this cycle, the first card is fed to the aperture A, meanwhile closing card lever contacts 41. Closure of contacts 41 completes a circuit through a relay coil F. A stick circuit for coil F is made, when contacts 41 open between cards, via contacts F1 and CF3. Coil F also closes contacts F2 which establish a shunt circuit around start key contacts 240, as follows: Line 191, normally closed contacts P1, now-closed contacts F2, stop key contacts 210 and now-closed contacts Q1, thence through magnet 28 and coil Q, in parallel, to line 192. During the next cycle, the first card traverses the first sensing station. Near the end of this cycle, card lever contacts 42 are closed to complete the circuit of relay N. Contacts N1 close and together with cam contacts CF5 which close during the period between cards when card lever contacts 42 open, provide a stick circuit for coil N. Coil N also closes contacts N2 which are in parallel with contacts F2 to provide an additional stick circuit for clutch magnet 28 and coil Q. In the later portion of the cycle in which the last card traverses the second

sensing station, the card lever contacts 42 open, and when the stick circuit of coil N opens at "14" (see Fig. 3) of the same cycle, coil N is deenergized. Both contacts N2 and F2 are then in open status, and the stick circuit of clutch magnet 28 and of coil Q breaks. Card feed operation will then be stopped at the end of the cycle.

It may be mentioned that cam contacts T8 open during a total-taking cycle to prevent the start key circuit from being effective.

Auto-control operation may be placed under control of photocells K or photocells N. The photocells K and N relating to a single pair of corresponding card columns are both connected at one side to an amplifier AMP. If photocell K is to be utilized, then the opposite side of this photocell is connected via a switch S to the amplifier, but if photocell N is to be utilized, the switch S is reversed to connect the opposite side of the photocell N to the amplifier. For the sake of simplicity, only the photocells Ka , Na , Kb and Nb and related amplifiers 1 and 2 for two pairs of corresponding columns to be sensed and compared are shown in Fig. 4, but it will be understood that duplicate arrangements are provided for the other such pairs of card columns.

Plugging is provided in the circuits for selectively placing the auto-control operation under control of photocells N according to the sensing and comparing of single-point, numerical data, or under control of photocells N according to the sensing and comparing of combinational point, alphabetic data, or under the control of photocells K according to the sensing and comparison of both alphabetic and numerical data on the same run of records.

Operation under control of photocells N in the sensing and comparing of numerical data will be considered first. Assume that the columns to be sensed and compared are those to which photocells Na , Ka , Nb , and Kb pertain. Since the photocells N alone are to be effective in the first case, the switches S (Fig. 4) are set to switch these photocells into circuit with their amplifiers. Plugwires (not shown) are connected from outlet sockets 550 and 551 of amplifier 1 to sockets 154 and 155, respectively, of the pick-up coil p of a duo-wound relay 1U and similar plug connection is made between amplifier 2 and coil p of relay 2U. Other plugging is between sockets 151 and sockets 156; also between sockets 566 and socket 561. Prior to starting operations, the operator also swings mirror M_2 (Fig. 1) to inactive position for a reason made clear soon. In the manner explained before, operations are started to feed the records.

During the third card cycle from the start, one card is traversing the second sensing station while the next card is traversing the first sensing station. At this time, the card lever relays F and N are both energized and have closed contacts F3 and N3. The amplifiers will thereby be conditioned for operation by a circuit from line 191, via cam contacts CF16, and relay contacts F3 and N3, through the amplifiers in parallel, and to line 192. Activation of a photocell Na by light will then be effective to cause the amplifier 1 to apply energizing potential via sockets 550 and 551, thence via plugwires (not shown) and sockets 154 and 155 to the coil p of relay 1U. Contacts 1Ua close to complete a circuit through the hold coil h of relay 1U, this circuit being from line 191 via cam contacts CF1, contacts 1Ua, through coil h, to line 192. Coil 1U shifts its contacts b to prevent a circuit being established through auto-control

relay coil P via the lower side of these contacts. Similarly, activation of photocell N_b during the cycle causes relay 2U to be effective to shift its b contacts. Thus, as long as agreeing perforations occur in corresponding columns of the leading and trailing cards respectively crossing apertures B and A, photocells N for these columns are activated. Clearly, then, if there is no change in group designations, all the plugged-in b contacts of relays U will have been shifted to prevent energization of auto-start coil P. It becomes clear now why, with the plugging for this first case, photocells N are utilized only for single-point, numerical group designation sensing and comparing and why mirror M₂ is placed in inactive position. If M₂ were in operative position, the photocells N would be energized by corresponding blank index positions of the cards at some time during the cycle. As a result, contacts b of relays U would be shifted to prevent pick-up of coil P regardless of whether or not agreeing perforations were subsequently sensed. Also, with the circuits plugged as described above, it is not intended to compare combinational-point, alphabetic data because the agreement of the first pair of perforations in corresponding columns will cause the relay U relating to these columns to be picked up and held, and a possible disagreement in subsequent index positions will have no effect.

If a disagreement in numeric group designating perforations occurs in any pair of corresponding card columns at the first and second sensing stations, then the related photocell N is not activated during the cycle. Accordingly, the contacts b of one of the relays U will not be shifted. A circuit will then be established upon closure of cam contacts CF13 at "13" of the cycle, from line 192 through coil P, a socket 151, the socket 156 plugged thereto, the normally closed side of contacts b of a deenergized relay U, the connected socket 566, the socket 567 plugged thereto, thence via cam contacts CF13, the card lever relay contacts N5 (now closed), and via cam contacts CF1 to line 191. Coil P, being energized, closes contacts P2 to complete a stick circuit for the coil from line 191 via cam contacts T10, relay contacts P2 and coil P to line 192. The cam contacts T10 will open, in the ensuing total cycle, to drop relay P.

Coil P, being energized, opens contacts P1, breaking the circuit of clutch magnet 28 and relay Q. With magnet 28 deenergized, the card feed clutch (not shown) will be disengaged at the end of the cycle in which the disagreement of group designations occurred. A total taking cycle may then be initiated in the manner described in the aforementioned patent.

Application of the invention to the sensing and comparing of numerical group data only on a run of records has been explained. The application of the invention to the sensing and comparing of alphabetic data only will next be described. In this application, photocells N are again switched into circuit with their amplifiers. The alphabetic code considered here as an example, is the two-hole code (see Fig. 2) wherein a perforation in one of index positions 1 to 9 and a perforation in one of index positions 0, 11, and 12 combine to designate a character. Agreement of such alphabetic data will be manifested by repeat activations of the photocells N during a record cycle. The first activation will pick up a relay U. The second activation will pick up a companion relay UN. The plugging for this case is as follows: From outlet socket 551 of amplifier 1 to socket 155 which

leads to one side of relay 1U and also is wired to one side of companion relay 1UN; from outlet socket 558 of amplifier 1 to a socket 574 which connects to one of the brushes 575 of a distributor CD2. The other brush of the distributor is wired to a plug socket 154 which, for this case, is plugged to socket 154. Socket 574 also is connected via a distributor EM1 to the coil p of relay 1UN. The distributors CD2 and EM1 are similar to the like designated elements disclosed in the aforementioned Patent 2,384,188. Distributors CD2 make at the 9, 8, 7 . . . 1 times of a cycle. Distributors EM1 make at 0, 11, and 12 cyclic times. The arrangement described above enables the amplifier 1, upon activation of photocell N_a, to pick up relay 1U at the 9, 8 . . . 1 cyclic times and to pick up relay 1UN at the 0, 11 or 12 cyclic time. A similar arrangement, including plugging and distributors, associates amplifier 2 with relays 2U and 2UN. The remaining plugging for the case under discussion is from a socket 577 to a socket 578, from a socket 579 to a socket 580, from a socket 581 to a socket 582, and finally from a socket 151X to a socket 158X which is wired via relay contacts 590a to the cam contacts CF13. As in the previous case, the mirror M₂ (Fig. 1) is set in its inactive position.

The agreement of perforations in index positions 1 to 9 of corresponding columns of the records traversing stations A and B (Fig. 1) results in activation of photocells N_a and N_b. Amplifiers 1 and 2 thereupon operate via distributors CD2 to pick up relays 1U and 2U which are held via their a contacts and cam contacts CF1 until "15" of the cycle (see Fig. 3). Relays 1U and 2U respectively close their contacts 1Uc and 2Uc. The agreement of perforations in positions 0, 11, and 12 of the records results in repeat activations of photocells N_a and N_b. Amplifiers 1 and 2 thereupon act via distributors EM1 to pick up relays 1UN and 2UN which are held via their contacts a and cam contacts CF1 until "15" of the cycle. Relays 1UN and 2UN close their respective contacts 1UNC and 2UNC. Cam contacts CF14 make shortly after "12" of a cycle and stay closed until "15." If agreement of the alphabetic group designations has been sensed in a cycle, the contacts c of relays U and UN are all closed. A circuit will then make from line 191 via CF14, plugging between 577 and 578, thence via contacts 1Uc and 1UNC to socket 579, plugwire (not shown) to socket 580, thence via contacts 2Uc and 2UNC to socket 581. The circuit is completed via the plugging between sockets 581 and 582, through relay 590, to line 192. Relay 590 opens its contacts 590a to prevent auto-control relay P from being energized when cam contacts CF13 close. If there has been a disagreement in alphabetic group designations, at least one of the contacts 1Uc, 2Uc, 1UNC and 2UNC will not be in closed status. Relay 590 will not be energized and contacts 590a will remain closed to allow coil P to be energized. As in the preceding case, energization of coil P causes the card feed to be interrupted.

The invention provides for the sensing and comparing of alphabetic and numeric group data on the same run of cards. For this third case, the photocells K are utilized. The plugging is from sockets 550 and 551 to sockets 154 and 155, respectively. As in the first described case, the sockets 157 are plugged to sockets 158. Further plugging is from sockets 585 to socket 567. For this third case, the mirror M₂ (Fig. 1) is set in active position.

As described before, a photocell K will be activated only if a pair of corresponding columns of cards traversing the first and second sensing station do not present perforations concurrently at apertures A and B. Whenever such disagreement occurs in any of the index positions 9 to 0, 11 and 12, photocell K is activated. In the manner previously explained, the connected amplifier then will apply energizing potential to the coil p of a relay U. The coil h of the relay U will then be energized. The relay U will shift its contacts b, closing the upper side of these contacts. During the closed interval of cam contacts CF13, coil P will be energized by a circuit such as previously traced except that the circuit this time extends through the upper, now-closed side of the relay contacts b and through a plug-wire (not shown) between socket 565 and socket 567.

While there have been shown and described and pointed out the fundamental novel features of the invention as applied to a preferred embodiment, it will be understood that various omissions and substitutions and changes in the form and details of the device illustrated and in its operation may be made by those skilled in the art, without departing from the spirit of the invention. It is the intention, therefore, to be limited only as indicated by the scope of the following claims.

What is claimed is:

1. In a machine having means to feed a plurality of records concurrently to spaced sensing stations, respectively, where the records are to be sensed and compared for agreeing and disagreeing relations of data designating light-pervious points in index positions of the records; a single sensing and comparing unit for the records at the spaced stations, said unit including an optical system of light projecting and reflecting elements to direct a single ray of light successively upon corresponding index positions of the records at the spaced stations to pass through any of the latter index positions which bears a light-pervious point or to be deflected by any blank one of these index points, so that the optical system in conjunction with the records at the spaced stations directs the ray of light into selective paths depending on agreeing or disagreeing relation of said corresponding index positions with respect to data designating light-pervious points, said unit further including a photo-sensitive element in one of said paths to be activated by the ray of light as a manifestation of one of said relations, and a machine-controlling circuit selectively governed by the photo-sensitive element according to whether or not the photo-sensitive element has been activated.

2. In a machine having means to feed a pair of records concurrently to spaced sensing stations, respectively, where the records are to be sensed and compared for agreeing and disagreeing relations of data designating light-pervious points in index positions of the records; a single sensing and comparing unit for the pair of records at the spaced stations, said unit including an optical system with means for directing a ray of light upon an index position of the record at one of said stations and through said index position if it bears a light-pervious point, said optical system including reflecting means to intercept the light ray passed through said index position and to re-direct the light ray upon the corresponding index position of the record at the other sensing station and through the latter index position if it bears a

light-pervious point, said unit further including a photo-sensitive element to receive and be activated by the light ray after passing through the corresponding index positions of the pair of records, and a machine-controlling circuit selectively governed by the photo-sensitive element according to whether or not it has been activated and, hence, according to whether or not the data-designating light-pervious points are in agreement or in disagreement.

3. In a machine having means to feed a pair of records concurrently to a pair of spaced stations, respectively, to be sensed for agreement or disagreement of data designating light-pervious points in index positions of the records; a single sensing and comparing unit for the records at the pair of spaced stations, said unit including an optical system of light-projecting and reflecting parts arranged for directing a single ray of light successively upon corresponding index positions of the records at the spaced stations and into one ultimate path if said corresponding index positions both bear light-pervious points and into a different ultimate path upon deflection of the light ray by either of said index positions lacking a light-pervious point, said unit further including a light-sensitive element in the latter path to be activated by the light ray as a manifestation of disagreement of the data designating light-pervious points in the records at the spaced stations, and a machine-controlling circuit selectively governed by said photo-sensitive element according to whether or not it has been activated.

4. In a machine such as defined in claim 3, the light-projecting structure including a source of light and means for focusing a light ray from said source upon an index position of one of the records to pass through a light-pervious point in said index position and the reflecting structure including means to intercept the light ray passing through said point and to re-direct the light ray upon the corresponding index position of the other record to be deflected by the latter index position, if lacking a light-pervious point, into the path intercepted by said photo-sensitive element for activating the latter element.

5. In a machine such as defined in claim 3, the light-projecting structure including a source of light and means focusing a ray of light from said source upon an index position of the record at one of said stations to be deflected by said index position, if lacking a light-pervious point, and the reflecting structure including a reflecting element to intercept the light ray deflected by said index point and re-direct it to the corresponding index position of the record at the other station to pass through the latter index position, if bearing a light-pervious point, and into the path intercepted by the light-sensitive element for activating the latter element.

6. In a machine having means to feed successive records synchronously across successive sensing stations where the records are to be sensed and compared for agreement or disagreement of record group-designating light-pervious points in index positions of the successive records; a single sensing and comparing unit for the records at the successive stations and including a photo-sensitive element, a source of light, a projecting element for projecting light from said source through a light-pervious point in an index position of the record at one said station, reflecting means for intercepting the light passing through and re-directing the light upon the corresponding index position of the record at the

11

other sensing station and thence, via a light-pervious point in the latter index position, upon said photo-sensitive element, so as to activate the photo-sensitive element upon agreement of group designating points in the corresponding index positions, the light being diverted from the photo-sensitive element by either of said corresponding index positions lacking a light-pervious point, and an auto-control circuit selectively governed by the photo-sensitive element according to whether or not the photo-sensitive element has been activated.

7. In a cyclically operating machine having means to feed a pair of records, during a cycle, synchronously across spaced stations where the records are to be sensed and compared for agreement or disagreement of combinations of data designating light-pervious points in index positions of corresponding columns of the records; a single sensing and comparing unit for the pair of records respectively traversing the spaced stations, said unit including a photo-sensitive element, a source of light, a projecting element for projecting a ray of light from said source upon one of the stations to scan the index positions of

12

a column of the record successively as the record is fed across the latter station, reflecting means for intercepting the light ray upon passing through a light-pervious point in an index position in the latter column and re-directing the light ray upon the corresponding index position, of the corresponding column of the record moving across the other station, and thence upon said photo-sensitive element via a light-pervious point in the latter index position, whereby the photo-sensitive element is activated upon each concurrence, during a cycle, of light-pervious points in corresponding index positions of corresponding columns of the pair of scanned records, the light being diverted from the photo-sensitive element by either of said corresponding index positions, lacking a light-pervious point, and machine-controlling circuit means selectively controlled by said photo-sensitive element according to whether the photo-sensitive element has been operated once or a plurality of times during the cycle.
